ORNAMENTAL TILE AND THE MOUNTING
THEREOF

Charles H. O'Koomian, Auburn, R. I.

Application February 3, 1931. Serial No. 513,130

10 Claims. (Cl. 72—19)

My present invention relates to the building art, and particularly pertains to the manufacture and the mounting of ornamental tiles.

The ceramic tiles heretofore used for bathrooms, hallways, and kitchens require expert workmanship in properly aligning and cementing the tiles so as to present a uniform appearance and a smooth, continuous surface. The setting of these tiles cannot be quickly done, and the procedure is therefore costly. One object of my invention is to devise a substitute tile which may be easily mounted, which is automatically aligned, and which does not require skilled labor for installing.

15 In addition, ceramic tiles are heavy and require steady and solid support surfaces which should remain in place without movement produced by settling of the house, temperature expansions and contractions, seasoning of the wood substructure, 20 and other similar conditions. Any disturbance of the support surfaces may cause a buckling or twisting of the solid tile surface and the production of unsightly cracks which mar the appearance of the tile surface. An additional object of my invention is to utilize a tile construction which 25 does not require cementing or rigid locking of the tiles to each other and which therefore permits a slight shift of the tiles when required to compensate for any changes or movement of the 30 support structure.

Ceramic tile walls have a further disadvantage in that it is extremely difficult to properly repair a cracked tile surface, the only practical way necessitating removal of the broken tiles and a resetting of new tiles. Such repair work is therefore a 35 costly operation requiring skilled workmanship; a further object of my invention is to so devise a tile construction that any cracked or broken tile may be readily replaced with very little disturbance to the remaining wall structure.

The standard ceramic tile therefore has constructional disadvantages as outlined above, and in addition, has further disadvantages because of the limitations of the manufacturing processes 45 and the physical characteristics of the resulting tiles. Thus, the glazing process limits the number of available colors, and the high cost of the tiles necessarily reduces the number of stock designs carried; in addition, the weight of the tiles 50 and their liability to chip and to break when subjected to sudden impacts increase the packing, shipping, and delivery costs. Additional objects of my invention are therefore to utilize a simple manufacturing process capable of producing an 55 unlimited number of different tile designs, the re-

sulting tiles being light in weight, without being brittle or fragile, thus decreasing the manufacturing, storage and merchandise costs.

With these and other objects and advantageous features in view, the invention consists of a 60 novel light weight tile and an improved mounting therefor, more fully disclosed in the detailed description following, in conjunction with the accompanying drawing, and more particularly defined in the appended claims.

65 In the drawing:

Fig. 1 shows a front elevation of a tiled wall utilizing the novel tiles;

Fig. 2 is a plan view of a single tile;

Fig. 3 is a back view thereof;

Fig. 4 is a back view of a plurality of assembled tiles, showing the interlocking features;

Fig. 5 is a section on the line 5—5 of Figure 4;

Fig. 6 is a section on the line 6—6 of Figure 1;

Fig. 7 is a section on the line 7—7 of Figure 1; and

Fig. 8 is a front elevation of a modified form of tile designed for direct mounting on standard frame studding.

It has been found desirable to manufacture a 80 tile of molded products, preferably of phenol condensation products, and to form each tile with interlock tongues and grooves for locking the tiles to each other and with securing tabs or the like for fastening to a support structure, 85 whereby the tiles may be readily mounted without requiring skilled labor and without the use of cement to lock the tile to the support, the finished tile section presenting a neat appearance simulating ceramic tile construction, but 90 possessing the important advantages of lightness, ability to give slightly in response to changes in or movements of the supporting structure, easy replaceability for repairs and the like, and having an infinite variety of color combinations, color schemes, and designs for a decorative effect; and the following is a detailed description of specific forms of tile construction which embody the principles of my invention.

Referring to Figure 1, a tile wall is preferably formed of a series of body tiles 10, footing tiles 11 and border tiles 12. Each body tile 10 as shown in Figures 2 and 3 is preferably of rectangular form, beveled at the corners as at 13, and provided with a tab 14 at one end thereof, 16 and two spaced tabs 15 at the other end thereof, the tabs 15 being provided with countersunk screw receiving holes 16 therethrough. Each tile 10 is formed with a lock groove 17 and tongue 18 at the back thereof adjacent the lower end,

and an extension 19 at the upper end thereof with a lock groove 20 and a tongue 21 positioned parallel to the upper edge of the tile.

The tabs 14 and 15 and the extension 19, as shown in Figures 3 and 5, have their front faces in the plane of the rear surface of the tile, and their rear faces aligned to form a supporting surface for the tile, additional braces or raised sections, such as shown at 22 in Figure 2, which may 10 if desired be formed as continuations of the tabs, being positioned wherever found necessary on the rear surface of the tile so as to form a solid support for the tile without complete filling in of the back of the tile and resultant increase in 15 weight and in cost.

As shown in Figure 5, the tabs 14 and 15 are positioned so that the tabs of adjacent tiles snugly dovetail. While this dovetailing is ample for all ordinary purposes, it is sometimes desirable to also pass a small nail through a suitable opening 23 in the groove 20 at the end remote from the countersunk openings 16 to also lock the tile at the corner, this feature being particularly advantageous when mounting the 20 initial tile of a row of tiles adjacent the corner of a room or the end of a wall or passageway.

As shown in Figures 6 and 7, the footing tiles 11 and the border tiles 12 are thicker than the tiles 10 and have curved edges in order to increase their attractive appearance. The footing tiles 11 may have square corners at the lower portions thereof as shown in Figure 6, or may have curved outwardly extending portions, not shown, to facilitate cleaning if desired. Instead 30 of utilizing single unit tiles such as shown at 10, large tiles 24 divided into sections as shown in Figure 8 may be directly attached to the frame studding, thus simplifying the mounting of the tiles and eliminating the need for a support 35 sheathing or the like. Preferably, the single tab on one side of the footing and border tiles is provided with a screw receiving opening, to simplify mounting.

The mounting of the tiles is a simple matter; the tabs on one side of a footing tile are cut off by a sharp knife or a saw, and the tile is locked in place on the supporting sheathing by screws through its opening 16. The footing tiles are then easily interlocked, each tile being secured 40 after interlocking with the previous tile. When the footing tiles are in place, the first row of main tiles is mounted in a similar manner, the lower tongue and groove of each tile locking 45 with the upper tongue and groove of the footing tile; the tab 14 of the corner or end tile is first removed by cutting with a sharp knife or saw to bring the tile in proper position, and the tabs 15 are locked to the sheathing by fastening screws, a nail being driven through the opening 23 if desired. The assembly is therefore a simple matter, each row of tiles being interlocked with the row below and the row above, and the tiles of each row being interlocked with each other, 55 the border tiles finishing the tiled portion in attractive manner.

If desired, the tiles may be mounted block fashion, or may be staggered as shown in Figure 1, sections of any desired length being easily 60 formed from the tiles by cutting.

The lateral extension of the projection 18 produces a further interlock, and is particularly useful when using vertical corner lock bars for concealing the corner joints, as these extensions 70 may be positioned beneath the lock bars and

securely held to the supporting sheathing by driving nails through the openings 23.

The molded tiles may be made in any desired colors and with any desired patterns or designs imprinted thereon; they are light in weight, fire 80 proof, water proof, are attractive in appearance, are easily cleaned, and may be readily mounted, removed, or repaired. The interlocking arrangement shown prevents passage of water between adjacent tiles, thus rendering the walls substantially waterproof, and permits slight movement 85 of each tile relative to the contiguous tiles, the extent of the movement being concealed to a large extent by the use of the beveled edges. If desired, the ends of the tiles may be dipped in suitable cement to further prevent leakage of 90 water.

The novel molded tiles have a further advantage, in that the preferred material, which is a phenol condensation product or the like is an insulating material. 95

While I have described specific structural forms of my invention, it is apparent that desired changes in size, in the arrangement of the interlocking features, and in the arrangement of the screw and nail receiving openings, may be made without departing from the spirit and the scope of the invention as defined in the appended 100 claims.

I claim:

1. A tile having a longitudinal lock groove adjacent the upper edge thereof, and a longitudinal lock groove adjacent the lower edge thereof, one of said grooves having an opening therethrough, and having an interlock tab extending laterally 110 from one side thereof, and an interlock tab out of alignment with said first tab extending laterally from the other side thereof, one of said tabs having an opening therethrough.

2. A tile having a longitudinal lock groove adjacent the upper edge thereof, and a longitudinal lock groove adjacent the lower edge thereof and oppositely directed to said first groove, one of said grooves having an opening therethrough, and having an interlock tab extending laterally 120 from one side thereof, and two interlock tabs out of alignment with said first tab extending laterally from the other side thereof, one of said tabs having an opening therethrough.

3. In a tile construction, a plurality of tiles 125 each having lock tongues and grooves adjacent their upper and lower edges and interlock tabs extending laterally from the sides, adjacent tiles being interlocked by their tabs and superimposed tiles being interlocked by their tongues and 130 grooves.

4. In a tile construction, a plurality of tiles each having lock tongues and grooves adjacent their upper and lower edges, said upper and lower tongues and grooves being oppositely directed, and interlock tabs extending laterally from the sides, adjacent tiles being interlocked by their tabs and superimposed tiles being interlocked by their tongues and grooves. 135

5. In a tile construction, a supporting base, a 140 plurality of tiles each having lock tongues and grooves adjacent their upper and lower edges, said upper and lower tongues and grooves being oppositely directed, and interlock tabs extending laterally from each side, the tabs on one side 145 being out of alignment with the tabs on the other side, the tabs on one side having openings therethrough, and securing means passing through said openings and engaging said supporting base, the adjacent tiles being interlocked 150

by their tabs and the superimposed tiles being interlocked by their tongues and grooves.

6. A tile having a body portion, a projection on one edge thereof with a lock groove and tongue in its upper surface, and interlock tabs on each side thereof, said projection and said tabs having their upper surfaces in the plane of the rear surface of the body portion.

7. A tile having a body portion, a projection on one edge thereof with a lock groove and tongue in its upper surface, and interlock tabs on each side thereof, said body portion having a lock groove and tongue in its rear surface adjacent the other edge, said projection and said tabs having their upper surfaces in the plane of the rear surface of the body portion.

8. In a tile assembly, a plurality of tiles each having a body portion, a projection on one edge thereof with a lock groove and tongue in its upper surface, interlock tabs on each side thereof and out of alignment with each other, said body portion having a lock groove in its rear surface adjacent the other edge, and said pro-

jection and said tabs having their upper surfaces in the plane of the rear surface of the body portion, whereby adjacent tiles are interlocked by their tabs and superimposed tiles are interlocked by their cooperating lock grooves and tongues.

9. A tile having a longitudinal lock groove adjacent the upper edge thereof, and a longitudinal lock groove adjacent the lower edge thereof, and having an interlock tab extending laterally from one side thereof, and an interlock tab out of alignment with said first tab extending laterally from the other side thereof.

10. A tile having a longitudinal lock groove adjacent the upper edge thereof, and a longitudinal lock groove adjacent the lower edge thereof and oppositely directed to said first groove, and having an interlock tab extending laterally from one side thereof, and two interlock tabs out of alignment with said first tab extending laterally from the other side thereof.
